UNITED STATES PATENT OFFICE

170,437

CRUTCH

Lorin A. Wood, Los Angeles, Calif.

Application April 22, 1953, Serial No. 24,613

Term of patent 14 years

(Cl. D83—1)

To all whom it may concern:

Be it known that I, Lorin A. Wood, a citizen of the United States and resident of Los Angeles, in the county of Los Angeles and State of California, have invented a new, original, and ornamental Design for a Crutch, of which the following is a specification, reference being had to the accompanying drawing, forming a part thereof.

Figure 1 is a side elevational view of a crutch, showing my new design;

Figure 2 is another elevational view taken from the right of Fig. 1; and

Figure 3 is a section taken on line 3—3 of Figure 1.

I claim:

The ornamental design for a crutch, substantially as shown.

LORIN A. WOOD.
